TRIGGER OPERATING MECHANISM FOR
AIRCRAFT GUNSWerner Christian Lassen Haubroe, Copenhagen,
DenmarkApplication January 5, 1933, Serial No. 650,239
In Denmark January 18, 1932

3 Claims. (CL 102-27)

The present invention relates to a trigger device for guns installed in aircraft and adapted for firing between the blades of the propeller, the trigger of the gun being for that purpose actuated 5 from a cam disk on the motor or propeller shaft, or a shaft driven synchronously therewith, by means of suitable intermediate members consisting mainly of two pistons adapted to slide each in one end of a tube, and of an intermediate 10 pressure-transmitting medium enclosed by the tube.

In order to minimize wear on such a trigger device, it will be necessary to maintain the same uncoupled locked, when firing is not going on, and 15 the device is only coupled in when firing is to be performed.

The invention has for its object to provide a locking and releasing arrangement for trigger devices of the kind mentioned above.

20 When the trigger device is locked, the firing will of course cease, as the locking prevents actuation of the trigger mechanism. In the automatic weapons here concerned, however, any firing is normally followed by a charging, and for 25 weapons adapted to fire between the blades of a propeller a suitable arrangement is therefore made that the loading mechanism will also be locked when the firing is to be discontinued, as otherwise the weapon would be left with a 30 cartridge in the chamber, which might result in spontaneous ignition of the said cartridge in the chamber due to the intense heat from the preceding firing and, therefore, an untimely firing. Such a locking of the loading mechanism must 35 be performed some suitable time before the trigger device is locked, so that the last insertion of a cartridge will be certain to be followed by at least one trigger action. This result can be attained by actuating the locking device of the loading 40 mechanism and that of the trigger mechanism, respectively by means of a separate grip for each, operated with a suitable delay between the two operations, but the actuation of both locking devices may be accomplished and, for the sake of 45 convenience in service should be done by means of one and the same grip, which may be arranged in such a manner that by a continuous motion the grip first effects the locking of the loading mechanism and then of the trigger mechanism, 50 but the grip may also and most suitably (viz in order to avoid too great motions of the operating grip) be arranged in such a manner that it will actuate the two locking mechanisms simultaneously, the locking mechanism for the trigger 55 device having then to be arranged in such a

manner that after having been actuated it will still allow a certain number of trigger actions to be performed before it automatically enters into the effective locking position.

The invention relates to the trigger mechanism with locking device but, not to the operating grip itself, which in the one as well as in the other construction is previously known.

Two different constructions of the invention are 65 illustrated in the drawings.

Figs. 1 and 2 show the part of a trigger mechanism with simple locking device that cooperates with a cam disk, in side elevation and in section, respectively.

Figs. 3 and 4 the corresponding part of a trigger mechanism with locking device for delayed locking, similarly in side elevation and in section, respectively, and

Fig. 5 the part of each of the two trigger mechanisms co-operating with the trigger device of the weapon itself.

In a casing 2 attached to the frame or motor of the flying machine a movable piston 1 is provided, which by means of a roller 3 and under the pressure from a spring 4 rests against the 80 edge of the cam disk 6 keyed to the motor or propeller shaft 5 a shaft driven synchronously thereto and, therefore, by the rotation of the said disk will be moved back and forth in the casing 2. The rear end of piston 1 is pressed 85 forward by the head 7 of another piston 8 adapted to slide in the end of a pipe 9, which is attached to the rear end of the cylinder 2 and, filled with a pressure-transmitting medium—for instance as shown a series of balls 10—leads 90 to the part of the trigger device of the arm shown in Fig. 5 and co-operating with the trigger of the weapon. The end of the pipe 9 is here attached, preferably in adjustable manner, in a nipple 11 at the bottom part of the trigger frame 95 12, in which the trigger in the shape of a lever 13, 14 is pivoted about a bolt 15. In front of the series of balls 10, a piston 16 is disposed in the end of the pipe 9 and adapted to slide therein, which piston is provided with a head 17 resting against a roller 18 mounted for rotation in the rear end of the trigger lever 13, 14, which is thus turned into the operating position when the pistons and the series of balls by action of the cam disk are driven in the direction towards the 100 trigger lever, the front arm 13 of which is actuated by a spring 19 so as to rock in the opposite direction, in such a manner that the roller 18 will constantly be maintained pressed firmly 105 against the piston head 17, and the pistons 16 110 against the piston head 17, and the pistons 16

and 8 with the intermediate series of balls will therefore be driven in the direction towards the piston 1, and will follow the same when the spring 4 moves the piston forward towards the shaft 5, after a cam on the cam disk 6 has passed the roller 3.

The adjustability of the pipe 9 in the nipple 11 on the trigger frame 12 may be provided by attaching the end of the pipe not in the nipple 10 itself but in a sleeve 20 threaded on the outside and screwed more or less deeply into the nipple.

It will be seen that there is really nothing to prevent the piston 1 from being firmly connected to the piston 8 so as to form a piston 1, 8.

15 The casing 2 may also be considered to be an extension of the pipe 9, and the piston 8 to belong to the pressure medium. It will then be seen that the piston 1 in every respect has to be considered to be a pipe-end piston in the pressure-transmitting device.

18 Figs. 1 and 2 show a locking and releasing device consisting of a spring-actuated bell-crank lever 23, 23', which is pivoted on the side of the casing 2 and is hook-shaped at one end to form a detent 21, which detent for the purpose of preventing the further operation of the trigger mechanism enters through the side of the casing adjacent to a cut-away portion forming a shoulder 22 on the piston 1, or 8, when the cam disk 20 has moved the piston as far away from the shaft as possible, unless the detent at the moment concerned might be maintained in released position. The release is effected by actuation from a Bowden cable 24 or similar device connected to the rear arm 23 of the bell-crank. As long as the Bowden cable is maintained taut, the detent will be out of engagement with the piston, and the trigger device will be free to operate. When the Bowden cable is released, 40 the detent will enter into its locking position, whereby the firing will be caused to stop in consequence of the trigger device being put out of operation.

43 Most suitably the locking device is arranged in such a manner that the same, after having been released for locking, will allow the cam disk to actuate the piston still a number of times before the locking becomes effective, and thereby a security will be attained for the insertion of a cartridge into the chamber being always followed by at least one trigger motion.

46 Such a locking device is shown in Figs. 3 and 4. Likewise as in the construction according to Figs. 1 and 2, a spring-actuated bell-crank lever 23, 23' is here pivoted to the side of the casing 2, and one arm 23 of the said lever is connected to a Bowden cable 24, but the other arm 23' of the bell-crank lever is here fork-shaped and has, instead of a fixed hook, a ratchet wheel 50 adapted to co-operate with the hook 22 on the piston 1. The ratchet wheel is actuated by a spring 26, Fig. 3, which tends to rotate the wheel in the direction of the inclination of the teeth of the said wheel, and which spring is tightened, when the wheel is rotated in the opposite direction. On the ratchet wheel a lug or pin 27 is provided, which by striking against tappets 28 and 29 on the arm 23' limits the rotation of the wheel in one or the other direction, respectively. On the arm 23 a spring-actuated check pawl 30 is pivoted, which engages the ratchet wheel when the latter is in engagement with the piston 1, but is automatically disengaged from the said wheel, when the latter, by the rotation 70 of the bell-crank lever produced by a pull on the

Bowden cable, is swung away from the piston, as the pawl for this purpose is provided with an arm 31 extending at an angle therefrom, which by such a rotation of the bell-crank lever comes into engagement with a stopping lug 32 fixed on the casing 2, thereby swinging the pawl on its pivot so as to release the ratchet for rotation under the action of its spring.

When the bell-crank 23, 23' is turned by means of the Bowden cable 24, while the cam disk 6 is rotating, the resulting action will be as follows:

During the first part of the motion the one tooth of the ratchet wheel that retains the piston in its rearmost position will release the same, in such a manner that by means of the spring 4 the roll 3 will be pressed against the cam disk 6, and now will follow the surface of the latter. During the continued motion of the bell-crank lever 23, 23', the nose 31 of the pawl 30 strikes the stopping lug 32, whereby the pawl is forced out of engagement with the ratchet wheel, which thus is now free and therefore while actuated by the spring 26, will rotate until the pin 27 strikes the tappet 28 on the bell-crank lever arm 23'. 95

When the pull on the Bowden cable 24 ceases, the spring-actuated bell-crank lever 23, 23' will swing out, in such a manner that the arm 23' will be moved towards the casing 2, and the teeth of the ratchet wheel 25 will engage the hook of the piston 1. For each motion of the piston the ratchet wheel will now be turned one tooth forward, and the check pawl 30 will prevent the ratchet wheel from turning back with the piston.

This is continued, until the pin 27 of the ratchet wheel strikes the tappet 29 of the arm 23. The piston 1 is then prevented from being moved forward, and the motion will cease. The piston will consequently have performed a number of motions forward and backward, after the pull on the Bowden cable has ceased, and will thus fire the shot, if the weapon has been loaded ready for firing, after the release of the Bowden cable.

The details of construction herein described are capable of modification without departing from the spirit and scope of the invention as set forth in the appended claims.

Having thus described my invention, what I claim is:—

1. Trigger mechanism for firearms, comprising in combination, a rotatable shaft, a cam disk carried by said shaft, a trigger-operating member, a tube disposed between said member and the cam disk, a pair of pistons reciprocable in opposite ends of said tube, one of said pistons having contact with the cam disk, means in said tube between said pistons for transmitting motion from one piston to the other, a spring-actuated bell-crank pivoted adjacent to one of said pistons, a spring-actuated ratchet wheel mounted for rotation in said bell-crank, the teeth of said ratchet wheel normally projecting into the path of movement of said piston, said piston having means engageable with the ratchet teeth when the piston is at the limit of its retractive movement in said tube thereby to rotate the ratchet wheel one tooth at each forward movement of the piston, means for limiting the rotary motion of said ratchet wheel, thereby to lock the piston against reciprocation, a pawl in engagement with said ratchet for holding it against rotation in the opposite direction under the tension of its spring, means for swinging said bell-crank on its pivot thereby to move the ratchet out of engagement with the piston, means automatically op- 150

erative during said movement to disengage said pawl thereby to release the ratchet for rotation under the action of its spring, and means for limiting said rotation.

5 2. Trigger mechanism for firearms, comprising in combination, a rotatable shaft, a cam disk carried by said shaft, a trigger-operating member, a tube disposed between said member and the cam disk, a pair of pistons reciprocable in opposite ends of said tube, one of said pistons having contact with the cam disk, means in said tube between said pistons for transmitting motion from one piston to the other, a spring-actuated bell-crank pivoted adjacent to one of said pistons, a 10 spring-actuated ratchet wheel mounted for rotation in said bell-crank, the teeth of said ratchet wheel normally projecting into the path of movement of said piston, said piston having means engageable with the ratchet teeth when the piston is at the limit of its retractive movement in said tube thereby to rotate the ratchet wheel one tooth at each forward movement of the piston, a pivoted pawl in engagement with said ratchet for holding it against rotation in the opposite 15 direction, means for swinging said bell-crank on its pivot thereby to move the ratchet out of engagement with the piston, means automatically operative during said movement to disengage said pawl thereby to release the ratchet for rotation under the action of its spring, a pin carried by said ratchet wheel, and a pair of tappets carried by said bell-crank at diametrically opposite points with relation to the ratchet wheel for engagement with said pin during rotation of the 20 ratchet wheel in opposite directions thereby to limit such rotation.
